SUBMERGED CHANNEL INDUCTION FURNACE

Filed Aug. 1, 1925

2 Sheets-Sheet 2

UNITED STATES PATENT OFFICE.

EDWIN F. NORTHRUP, OF PRINCETON, NEW JERSEY, ASSIGNOR TO THE AJAX METAL COMPANY, OF PHILADELPHIA, PENNSYLVANIA, A CORPORATION OF PENNSYLVANIA.

SUBMERGED-CHANNEL INDUCTION FURNACE.

Application filed August 1, 1925. Serial No. 47,593.

The purpose of my invention is to provide submerged molten resistors for induction electric furnaces, which shall have good heating capacity and adaptability to different metals and alloys, and which at the same time shall be effective to secure good circulation of the molten metal.

A purpose of my invention is to stagger the two parts of a channel which lie on opposite sides of the central transformer leg laterally with respect to the winding, whether a central core winding or pancake side winding be used.

A further purpose is to stagger the top and bottom of a resistor channel laterally with respect to the winding whether with an enclosed core winding or with pancake coils.

A further purpose is to form a channel in which the variant distances between the middle portions of upwardly and downwardly extending limbs at corresponding sections of the limbs is different from the distances between their edges.

Further purposes will appear in the specification and in the claims.

I have preferred to illustrate my invention by a number of different forms, and recognize that a great many additional forms of my invention will appear to those skilled in the art in view of my disclosure herewith.

I have selected the forms shown among the larger number, therefore, with a view to illustrating the principles thereof to best advantage by practical construction by which the principles may be applied.

Figure 1 is a top plan view of one form of my invention showing a double channel.

Figure 2 is a section of Figure 1, taken upon line 2—2 of Figure 1.

Figure 3 is a section of Figure 2, taken upon line 3—3 thereof.

Figure 4 is a front elevation of the structure of Figure 1.

Figure 5 is a vertical section of a second form.

Figure 6 is a top plan view of a third form of my invention.

Figure 7 is a section of Figure 6, taken upon line 7—7 thereof.

Figures 8, 9, 10, 11, 12 and 13 are sections

corresponding to line 8—8 of Figure 7, showing different cross sections of the channel passage, which may be used in the form 55 of Figure 6, or for any of the channels shown in the other figures.

Figure 14 is a top plan view of a fourth general form of my invention.

Figure 15 is a section of Figure 14, taken 60 upon line 15—15 thereof.

Figures 16 and 17 are sections of Figure 15, taken upon lines 16—16 and 17—17 thereof.

Figures 18 to 26 inclusive are cross sections corresponding in position with section line 17—17, showing suggested forms of cross section of channel opening for use with pancake windings, double pancake windings being shown in Figures 18 and 23 inclusive, 70 and single pancake windings in Figures 24 to 26 inclusive.

Figure 27 is a vertical section of another form, the view corresponding with that of Figures 2, 5, 7 and 15.

In the drawings similar numerals indicate like parts.

I have shown illustrations based upon several different principles by which circulation is secured.

Taking up the several figures, and explaining them in illustration and not in limitation:

In Figures 1 to 4, a double staggered form of channel is shown which may be compared with the staggered single channel shown in Figure 13, differing from it in having two of these staggered channels reversely sloping and communicating at the bottom.

A crucible 30 is shown, having pool space 90 31, usual pouring spout 32 and metallic supporting casing 33, suitably interrupted for convenience of insertion, if the crucible be separately formed, or for ramming if the material of the crucible is to be rammed in 95 place, and also interrupted to prevent flow of eddy currents.

A suitable transformer is shown at 34, illustrated as of the shell type, with a winding 35, upon the middle leg 36, so that the 100 winding is enclosed by the channel.

The submerged channel 37 is shown as comprising two channel sections 38 and 39 oppositely staggered so as to provide legs

40 and 41 of channel 38, and legs 42 and 43 of channel 39. The legs of these staggered channels meet at the bottom in a relatively sharp angle 44 so that the parts of the channel about the angle react upon each other to secure motor effect drive up the outsides of the channel, with gravity return down the insides of the channel as in Wyatt Patent No. 1,201,671. There is also some attraction of the currents flowing in the same direction in the diverging paths shown, as discussed in Wyatt Patent No. 1,312,069, in connection with Figures 10-12.

The lateral staggering of the channels results in a difference in pressure laterally (parallel to the axis of the winding) at the bottom with respect to the top, due to reaction of primary on secondary in their entireties, so as to vary the flow, causing the metal to flow up somewhat more along the outer lateral sides of the channel than would otherwise be the case. These several forces will of course be proportioned by the designer according to the character of circulation sought.

The character of circulation obtained will be that of the dominating force, causing circulation slightly modified by the other forces indicated, i. e., the path will be cleared and the metal will be moved forcibly by the dominating circulation and that flow due to other causes will combine with it, slightly modifying its position, but without substantial modification of its general direction.

At the top of the channels the floor of the pool is grooved as seen in solid lines in Figure 1, and as shown by the space 45, in Figure 2, the grooving extending downwardly along curved lines as shown at 46 in Figure 2.

Convenient trunnion supports are shown at 47.

In Figure 5 the illustration is intended to be substantially the same as in Figures 1-4, except that the lower portion of the channel is curved instead of being extended downwardly along straight sides to an angle, the curvature of the lower portion at 48 being shown as concentric with the transformer leg and winding. The two staggered channels come together at the bottom at 44'. Here reliance for circulation is placed upon lateral staggering of the channel portions with respect to the winding and upon pinch pressure, present in all such channels.

In Figures 6, 7 and 8 the single channel 49 is not laterally staggered, but the outer lateral edges 50 are closer to the winding than the central portion 51, with the result that the reaction of secondary upon secondary, producing motor effect drive, greatest at the point 44 as in the Wyatt Patent, No. 1,201,671, is assisted by the reaction of primary upon secondary, causing a greater

pressure at the edges than at the middle of the channel at any portion of its length, with the result that the upward flow takes place chiefly along the middle of the width of the channel, with a relatively larger flow downwardly along the outer edges of the channel.

In the form shown in Figure 9 the middle of the channel 51, considered laterally, is nearer to the winding than outer edges 50, resulting in just the reverse of the distortion of flow taking place in the form of Figures 6-8. As a result the greater flow is up along the outer edges and down along the middle portion of the channel.

In the sections in Figures 6, 8 and 9 the halves of the channel are straight meeting at the center in the sections. In Figures 10 and 11 much the same cross section, effectively, is curved. Figure 10 corresponds generally in its operation to 51' and down along the edges 50', while the flow in Figure 11 will be up along edges 50' and down along middle 51'.

In Figure 12 the sections of the two channel legs are sloped laterally, being nearer at the edges 50², at any given height, than they are at the edges 51², with the result that the greater flow upwardly will take place at or near the edges 51², and the greater flow downwardly at or near the edges 50².

In Figure 13 a single staggered lateral channel 38' is shown, differing from the channel 38 in the fact that the cross sections of the channel portions are parallel not only with each other, but with the axis of the transformer leg, whereas the cross sections in Figure 1 are at an angle relatively with respect to the axis of the channel leg, tending to increase the amount of flow of molten metal up that corner of each of the cross sections further from the transformer winding and from each other, and down that corner of each of the cross section edges nearer to the transformer winding.

In Figures 14-17 the channels 38² are further from each other at the bottom than at the top, which would cause circulation whether the enclosed winding were used, or with pancake windings 52 of which two are shown in these figures. The pancake windings result in a pressure of a metal toward the space in the center upon them, causing the metal to flow upwardly along those sides 53 of the channel toward each other with consequent gravity downward flow of cooler metal along the other sides 54 of the channel.

In Figure 18 the two legs of the secondary channel are of rectangular cross section parallel to the axis of the coil and are not laterally offset with respect to each other. The alternating current passing through the pancake coils causes upward flow of molten metal along the center lines 54 of these channels with consequent gravity downward flow of molten metal along the edges 55.

The form shown in Figures 19 and 20 generally corresponds to those shown in Figures 8 and 9, and those in Figures 21 and 22 to the forms shown in Figures 10 and 5 11, with the differences, however, that the current in the pancake coils causes repulsion of metal to the center and upward flow of metal along the middle, as at 51 and 51', with downward flow of metal along the outer 10 edges 50 and 50'.

Figure 23 corresponds generally with Figure 17 except that the two channels 38' come together at the bath to a single opening on each side.

15 A single pancake coil only is used in Figure 24 and in Figures 25 and 26, as could be the case in any of the figures. The section in Figure 24 is like that of Figure 19. The force from the single pancake coil would 20 tend to drive the molten metal toward that edge of the channel furthest from it. With slight eccentricity this would mean merely that more metal would go up the leg further from it than the nearer leg, and more metal 25 would come down by gravity flow along the nearer leg than that further from it. If the difference in pressure were great enough this would result in unidirectional flow.

In Figure 25 the general arrangement of 30 channel sections is that of Figure 12, but the single pancake coil would cause molten metal to come up the edges of the channel further from the coil with gravity flow down along the nearer edges.

35 In Figure 26 the single pancake coil would drive the metal away from the coil, tending to produce uni-directional flow up the leg of the channel further from the pancake coil with gravity return along the nearer leg.

40 In Figure 27 the pancake coil is used with a channel whose lower part is concentric with the coil. As in Figures 15-25 single or double pancake coils could be used.

45 It will be noted that the crucibles in Figures 14-27 all lack the metallic casing shown in Figures 1-13.

In view of my disclosure herein various other forms will appear to those skilled in the art embodying all or a part of the benefit 50 of my invention. It is, therefore, my intention to cover herein all such as come within the reasonable spirit and scope of my invention.

Having thus described my invention, what 55 I claim as new and desire to secure by Letters Patent is:—

1. In an electric induction furnace of the submerged resistor type, a channel resistor unsymmetrical on opposite sides of the 60 secondary having two end connections with the furnace staggered laterally of the winding, a transformer core threading the resistor and a transformer winding upon the core, the current in which exerts different pressures upon the two branches of the resistor

at the same heights thereof and causes flow by reason of the lack of symmetry of the secondary.

2. In an induction furnace having a pool, a single passage submerged channel resistor 70 beneath the pool, connecting therewith, a transformer leg threading the resistor and a winding at some point upon the leg, the novelty which consists in staggering the entire resistor both axially and angularly 75 with respect to the coil axis.

3. A furnace having a pool, in combination with walls enclosing a submerged loop resistor for the pool, the horizontal sections of the resistor being concave on one side and 80 convex on the other.

4. In an induction furnace having a pool, the combination of walls to enclose a resistor beneath the pool and connecting therewith having, in horizontal sections, concave resistor sections facing each other in opposite 85 legs of the resistor, a transformer having a leg interthreading the resistor and a winding upon said leg enclosed by the resistor.

5. In an induction furnace, walls forming 90 a pool and a channel beneath the pool having an acute angle at the bottom of the channel and having a channel cross section in horizontal planes concave on one side and convex on the other in combination with a transformer having a leg threaded through the resistor and a winding at some point upon the leg.

6. In an induction furnace, walls forming 100 a pool and a channel beneath the pool having an acute angle at the bottom of the channel and a channel cross section in horizontal planes concave on one side and convex on the other, in combination with a transformer having a leg and winding threaded through 105 the resistor.

7. In an induction furnace having a pool, walls forming a channel beneath the pool having an acute angle at the bottom of the channel and a channel cross section in horizontal planes concave on one side and convex on the other in combination with a transformer having a leg threaded through the resistor and a winding outside said resistor and adapted to move the metal toward 115 one edge thereof.

8. An induction furnace having a transformer and a pool and walls forming a single passage channel beneath the pool for the secondary, the channel having rectangular horizontal channel cross sections in the different parts at an angle with respect to the axis of the transformer winding and to each other, in combination with a transformer leg interthreading the secondary and 120 a winding on said leg enclosed by the resistor.

9. An induction furnace having a transformer and a pool and walls forming a single passage channel beneath the pool hav- 125 130

ing rectangular horizontal channel cross sections in the different parts at an angle with respect to the axis of the transformer in combination with a transformer leg inter-
5 theading the secondary and a winding on said leg enclosed by the resistor.

10. An induction furnace having a pool, a transformer having a central leg and a winding on the leg, in combination with walls forming a single passage resistor channel enclosing said winding, the horizontal cross sections of the resistor being longer in one direction than in the opposite direction and having the longer direction at an angle
15 with respect to the axis of the coil.

11. In an induction furnace having a pool, walls forming a plurality of channels beneath the pool, a transformer core threaded through said walls and a pan-cake winding about said core, the channel sloping with respect to the plane of the pan-cake coil.
20

12. In an induction furnace having a pool,

walls forming a channel beneath the pool, a transformer core threaded through said channel and a pan-cake winding about said core, the channel sloping with respect to the plane of the pan-cake coil.
25

13. In an induction furnace having a pool, walls forming a channel beneath the pool having in horizontal cross sections the channel sections of opposite resistor legs at an angle to each other, a transformer core threading the resistor and a pan-cake coil at one side of the channel adapted to press the molten metal to the opposite side thereof.
30

14. An induction furnace having pan-cake coil transformer means for circulating molten metal, a pool, and walls forming a resistor channel beneath the pool in which opposite legs of the channel are staggered with respect to the coil.
35

EDWIN F. NORTHRUP.
